GLASS-CUTTING MACHINE

Georges Henry, Dampremy, Edgard Brichard, Jumet, and Marc Delacuvellerie, Lovelval, Belgium, assignors to Union des Vergeries Mécaniques Belges, Société Anonyme, Charleroi, Belgium, a Belgian company

Application December 20, 1945, Serial No. 636,104
In Belgium March 2, 1945

11 Claims. (Cl. 33—32)

1

This invention relates to cutting glass sheets by drawing two series of cutting lines, which lines are usually at right angles to obtain rectangular panes, but may also be at any other angle.

In existing machines adapted to cut glass by drawing two series of parallel cutting lines at right angles to each other, it is necessary to interrupt the drawing of said lines in order to perform various operations such as positioning, transporting and removing the glass sheets and also enabling the cutting tools to perform their return stroke. These repeated interruptions give rise to considerable loss of time and to a substantial reduction in the output of the machine.

The object of the present invention is to obviate these inconveniences and to carry out the operations as a cycle in which the cutting lines are drawn in succession without interruption. To this end, according to our invention a series of parallel lines are drawn by a set of travelling tools while the glass sheet is stationary, and the other series of parallel lines are drawn by a set of stationary tools while the sheet moves towards or away from its stationary position, and simultaneously the travelling tools are caused to perform their return stroke. A fresh sheet being brought forward after each sheet has been cut, the position after one cycle of operations is such that a new identical cycle can be started without any interruption taking place in drawing the cutting lines.

A further object of this invention is to provide a machine for carrying out the above process, such machine having two sets of tools, one being movable relatively to the machine frame, the other being stationary and placed in front of or behind the path covered by the movable or so called travelling tools, so that the sheet subjected to the action of the travelling tools be cut by the stationary tools either when it moves towards the requisite position under the travelling tools, or away from such position. The machine also comprises various auxiliary mechanisms, in particular means for transporting the glass sheet, for operating the travelling tools and the stationary tools, for adjusting the position of the sheet relatively to the tools and for adjusting the position of one set of tools relatively to the other.

The features of the invention will be described in detail with reference to the accompanying drawings which illustrate, by way of example, an embodiment of the new machine in which the glass sheet is successively subjected to the action of the travelling tools and of the stationary tools.

In the drawings:

Fig. 1 is a general view of the machine in side elevation,

2

Figs. 2 and 3 show a plan view and a front elevation respectively of the same machine;

Figs. 4 to 12 illustrate on a larger scale constructional details of the machine,

5 Fig. 4 showing a detail of the transporter guiding means,

Fig. 5 being a view of the carriage carrying the travelling tools,

Figs. 6 and 7 being vertical sectional views of 10 the means for operating the travelling tools, taken on lines VI—VI and VII—VII respectively of Fig. 8,

Fig. 8 being a plan view corresponding to Figs. 6 and 7,

15 Figs. 9 and 10 being enlarged sectional views of the means for operating the stationary tools, taken on lines IX—IX and X—X respectively of Fig. 2,

Figs. 11 and 12 being a front elevation and a 20 side elevation respectively of a stop for adjusting the position of the glass sheet.

Fig. 13 is a diagram of electrical connections for the operating means.

Fig. 14 is a fragmentary side elevational view 25 of a ramp provided for raising the travelling tools at the end of the cutting operation thereof.

The machine illustrated comprises essentially three main parts, to wit, a conveyor, a travelling carriage adapted to move above one portion of the conveyor transversely thereof, and a set of tools mounted in fixed position above the other portion of the conveyor so as to cut the glass sheet moving along said portion.

The conveyor comprises an endless carrier 30 formed of straight cross-boards or slats secured to two or more endless chains 2 (Fig. 3) and provided with bearing plates 3 having V-shaped grooves sliding on guide rails 4 (Figs. 2, 3, 4) extending longitudinally of the machine, said rails being carried by cross bars 5 which in turn rest on the machine frame 6 (Fig. 1).

The endless chains 6 mesh with gears 7 rotated by a motor 8 through a reducing gear and a clutch (not shown). The motor 8 may also operate in synchronism auxiliary conveyors arranged in front of or behind the conveyor 1. In Figs. 1 and 2 we have shown at 9 a conveyor arranged in front of conveyor 1 and operated from the latter through the chain 10.

50 Secured above the front portion of conveyor 1 are cross bars 11 carrying rails 12 on which runs a carriage 13 provided with bearings 14 in which is journalled an oscillating shaft 15 carrying cutting tools 16 (Fig. 5).

55 The carriage 13 has wheels 17 with horizontal axes and it is guided along the rails 12 by rollers 18 with vertical axes, which are spring-pressed

3

against the sides of the rails 12. On the carriage 13 is mounted a motor 19 which, through the intermediary of a reducing gear 20 (Fig. 2), rotates a shaft 21 carrying pinions 22 (Fig. 5). These pinions mesh with a chain 23 which extends between brackets 24 on the machine frame and passes on tensioning pinions 25 so that rotation of the shaft 21 in one or the other direction causes the carriage 13 to move forward or backward on the rails 12 along a strictly rectilinear path across the conveyor 1.

The movement of the carriage 13 is controlled by operating a hand switch 26 (Figs. 2, 3 and 13) which starts the motor 19 and is thereafter substituted through the action of a relay (not shown) by a switch 27 operated at the end of the return stroke. At the end of its operative stroke the carriage strikes against the change-over switch 28 which causes the motor 19 to start again in reverse direction and causes the carriage to return to its starting point. At the moment of reaching same the carriage operates the switch 27 and thus brings about its own stoppage.

On the other hand, at the end of its operative stroke the carriage 13 which carries an abutment 29 causes the same to operate a switch 30 which through the intermediary of a relay 40 (Fig. 13) sends current to the motor 8 and starts the movement of the conveyors 1 and 9. Thus, feeding of the glass sheet takes place during the return stroke of the carriage 13.

For the sake of clearness, the carriage 13 as illustrated in Fig. 2 is supposed to have been pushed beyond the end of its stroke, it will be understood that the switches 27, 28 are adjustable in position along the rails 11 according to the width of the sheets to be cut.

The throwing into and throwing out of operation of the cutting tools 16 are conveniently controlled by the mechanism illustrated in Figs. 6 to 8. In this mechanism each tool 16 is carried by an arm 31 rigid with a hub 32 loosely mounted on shaft 15. The arm 31 is adapted to be lifted by a yoke 33 carried by collars 34 secured to the shaft 15.

Another collar 35 also secured to the shaft 15 carries a finger 36 which, at the end of the operative stroke of carriage 13, engages a ramp 420 (Fig. 14) whereby it is lifted, causing the shaft 15 to oscillate and to swing upwardly the yoke 33 and therewith the arm 31 and the tools 16, the position then being as shown in dot-and-dash lines in Fig. 6 and in full lines in Fig. 7.

At that moment a projection 37 on the collar 35 is engaged by a latch 38 pivoted at 39 to the side wall of carriage 13 and pressed by a spring 41 against the periphery of collar 35. The tool carrying arm 31 thus is maintained in raised position during the entire inoperative or return stroke of the carriage 13. At the end of that stroke the finger 36 engages a ramp 42 and causes the shaft 15 to turn and move the projection 37 away from the latch 38 while the tail piece 43 of the latch strikes against a spring stop 44, whereby the latch is lifted and disengaged from the projection 37.

The movement of the carriage 13 then being reversed the finger 36 rides down the ramp 42, the tools 16 are gradually lowered onto the glass and a new operative stroke begins. The latch 38 drops on the collar 35 beyond the projection 37 and is ready to catch same as soon as the tools 16 are again lifted.

As above stated, the motor 8 operating the conveyors 1 and 9 is started by the closing of

4

switch 30 at the end of the operative stroke of the travelling tools 16. The glass sheet thus is fed from the front portion of conveyor 1 situated under the rails 12 to the rear portion which is situated beyond said rails, the stationary tools 45 being located at the entrance to said rear portion.

The tools 45 are carried by arms 46 loosely mounted on a shaft 47 which extends across and above the conveyor 1 and is adapted to oscillate in bearings 48 carried by side plates 49 adjustably secured to the frame 6 of the machine. The operation of the tools 45 is controlled electrically by means of a switch 50 which is operated by the edges of the glass sheet in the following manner.

Normally the tools 45 are held in the raised position by an electro-magnet 51 whose armature is mounted at the end of an arm 52 secured to the shaft 47 on which are also secured yokes 53 for lifting the tool carrier arms 46. When the conveyor 1 brings the leading edge of a sheet under the tools 45, this edge engages the switch 50 (Figs. 10 and 13) which opens, de-energises the electro-magnet 51 and allows the tools 45 to drop onto the glass by the action of gravity. In order to avoid premature dropping of the tools and shocks liable to injure same, their downward movement is slowed down by a cam 54 of decreasing radius (Fig. 9) which is pivoted on an arm 55 secured to the shaft 47. When the tools 45 are raised, the cam 54 glides without pressing on the surface of the glass or, as shown, on the periphery of a pulley 56 or other surface moved in synchronism with the glass. As soon as the shaft 47 is freed by the electro-magnet 51, the weight of the parts carried thereby rests through the cam 54 on the pulley 56; the cam then revolves on the pulley and the tools are gradually brought down until they bear on the glass.

The cam 54 thus serves a twofold purpose: it slows down the drop of the tools so as to avoid a violent contact with the glass and it retards the moment when they touch the glass until the edge of the glass sheet has moved to the desired position with respect to the starting point of the cutting line.

When the trailing edge of the glass sheet passes under the switch 50, the latter is closed by the action of a spring, the electro-magnet 51 draws its armature and lifts the tools before they are reached by the trailing edge. In its lifting movement, the armature of electro-magnet 51 temporarily closes a contact 57 (Figs. 2 and 13) which acts on relay 40 to cut the current in the conveyor motor 8. When the conveyor stops, the glass sheet has been scratched in two perpendicular directions and is ready to be removed from the machine.

The cycle of operations which thus has been completed comprises two stages comprising each several simultaneous steps:

In the first stage, which starts when the machine is started by the operator, the conveyors 1 and 9 are stationary and the travelling tools perform their operative stroke, the operations being as follows:

(1) The sheet *a* (Fig. 1) which had been scratched in both directions in the course of the preceding cycle is removed, or severed and the severed panes are removed from the machine;

(2) The sheet *b* which in the preceding cycle had been brought under the travelling tools 16, is scratched by said tools in a direction at right

angles to the direction of movement of the conveyor;

(3) A sheet *c* is placed on the auxiliary conveyor *9* in front of the main conveyor *1*.

The second stage, during which the conveyors are in operation, is automatically controlled by the operation of the change-over switch *28* and of the switch *30*. It comprises the following simultaneous operations:

(4) The conveyor *1* is set into motion; it carries the sheet *b* under the stationary tools *45* which are brought down and draw the second series of cutting lines in a direction parallel to the movement of the conveyor, while the sheet moves away from the working zone of the machine;

(5) The carriage *13* with the travelling tools *16* thereon moves back to its starting point, the tools *16* being lifted;

(6) The sheet *c* is carried by the conveyor *9* onto the conveyor *1* and comes to a stop under the carriage *13*, while at the same time the stationary tools *45* are lifted.

The cycle then is completed: the machine is in the same position as it was when starting: a sheet has been scratched and removed and a fresh sheet has taken its place and is in working position.

The distance *d* between two successive sheets on the conveyor is determined by the distance between the leading edge of the sheet positioned under the carriage *13* and the stationary tools *45*. As this distance corresponds to a space on the conveyor which is not utilised, it is of course desirable that said distance be as small as possible in order to increase the output of the machine. It cannot be reduced to zero, but it is possible to reach the same result, as regards the output, by making said distance *d* equal to the length of a glass sheet, or to a multiple of such length. It is then possible to place in the free interval one or more additional sheets on the conveyor so that the sheets thereon follow each other without any substantial interval, and the movement of the conveyor, during one cycle, is reduced to the length of one sheet.

This condition can be easily fulfilled by adjusting the position of the said plates *49* on the machine frame *6*, according to the length of the sheets to be cut, provided of course such length remains uniform. The operations are carried out as described above with this difference only, that two different sheets are successively scratched, one lengthwise, the other crosswise, but as before, a sheet scratched in both directions is delivered by the machine at the end of each cycle.

It is of importance that the position of each sheet be correctly determined in the transverse as well as in the longitudinal direction.

In order to determine the position of the sheet in the transverse direction, so that the width of the uncut side edges be uniform, we use an adjustable abutment *58* (Fig. 2) mounted for example in a guide *59* at right angles to the conveyor *9* and actuated through rod and crank *60*, *61* by a motor *62* when the switch *50* energises the electro-magnet *51* controlling the lifting of the tools *45*. The positioning of the sheet thus takes place while the conveyors *1* and *9* are stationary.

The longitudinal position of the sheet under the travelling carriage *13* is controlled by a stop *63* (Figs. 1, 11 and 12) which is pivoted at *64* to the machine frame and is pressed against the

conveyor *1* by a spring *65* so that it catches the leading edge of the sheet fed under the carriage *13*. Before the conveyor is set in motion, the stop *65* is automatically raised by a cam *66* secured to and extending under the carriage *13*. When the carriage *13* reaches the end of its operative stroke and the conveyor is started, the cam *66* engages under a nose *67* rigid with the stop *65* and lifts said stop for the time necessary to enable the leading edge of the sheet to pass thereunder. It moves down during the return stroke of the travelling carriage and is again in its position of engagement when the next sheet arrives.

It is understood that modifications may be made in the machine described without departing from the scope of the invention. Thus the sequence of the two process stages forming a cycle may be inverted without changing the result or the total duration of these operations. It is only necessary to that end to place the stationary set of tools *45* in front of the travelling carriage and to change accordingly the electric connections.

The means for operating the stationary and the travelling tools may also be substituted by equivalent means, for example with pneumatic instead of electric control.

It should also be understood that the machine may be arranged for cutting the glass in two directions at any angle to each other, or even in parallel directions, one set of cutters then drawing lines in alternating relation to those drawn by the cutters of the other set.

We claim:

1. In a machine for cutting glass the combination of a machine frame, an endless conveyor on said frame, said conveyor being of sufficient length to carry at least two sheets of glass in alignment, a carriage travelling above and across a part of said conveyor, a set of cutting tools on said carriage, a stationary shaft on said machine frame extending over and across said conveyor, a set of cutting tools on said shaft, means for intermittently moving said conveyor, means for causing the tools on said travelling carriage to operate on a glass sheet while said sheet is stationary, means for causing the tools on said stationary shaft to operate on a glass sheet while said sheet is moving thereunder, reciprocating means for determining the position of the glass sheets on said conveyor transversely thereof, and means actuated by said carriage for determining said position in the longitudinal direction.

2. In a machine for cutting glass the combination of a machine frame, an endless conveyor on said frame, said conveyor being of sufficient length to carry at least two sheets of glass in alignment, a carriage travelling above and across a part of said conveyor, a set of cutting tools on said carriage, a stationary shaft on said machine frame extending over and across said conveyor, a set of cutting tools on said shaft, means for intermittently moving said conveyor, means for causing the tools on said travelling carriage to operate on a glass sheet while said sheet is stationary, means for causing the tools on said stationary shaft to operate on a glass sheet while the sheet is moving thereunder, a lateral abutment for determining the position of a glass sheet on the conveyor transversely thereof, and means for imparting to said abutment a reciprocating movement laterally towards and away from said conveyor.

3. In a machine for cutting glass the combination of a machine frame, an endless conveyor on said frame, said conveyor being of sufficient length to carry at least two sheets of glass in alignment, a carriage travelling above and across a part of said conveyor, a set of cutting tools on said carriage, a stationary shaft on said machine frame extending over and across said conveyor, a set of cutting tools on said shaft, means for intermittently moving said conveyor, means for causing the tools on said travelling carriage to operate on a glass sheet while said sheet is stationary, means for causing the tools on said stationary shaft to operate on a glass sheet while the sheet is moving thereunder, a lateral abutment for determining the position of a glass sheet on the conveyor transversely thereof, and means for imparting to said abutment a reciprocating movement laterally towards and away from said conveyor.

tion of a machine frame, an endless conveyor on said frame, said conveyor being of sufficient length to carry at least two sheets of glass in alignment, a carriage travelling above and across a part of said conveyor, a set of cutting tools on said carriage, a stationary shaft on said machine frame extending over and across said conveyor, a set of cutting tools on said shaft, means for intermittently moving said conveyor, means for causing the tools on said travelling carriage to operate on a glass sheet while said sheet is stationary, means for causing the tools on said stationary shaft to operate on a glass sheet while the sheet is moving thereunder, a stop for determining the correct position of a glass sheet on the conveyor longitudinally thereof, said stop being normally held in the path of the glass sheets, and means operative when the conveyor starts moving to move said stop out of the path of the glass sheets.

4. In a machine for cutting glass the combination of a machine frame, an endless conveyor on said frame, said conveyor being of sufficient length to carry at least two sheets of glass in alignment, a carriage travelling above and across a part of said conveyor, a set of cutting tools on said carriage, a stationary shaft on said machine frame extending over and across said conveyor, a set of cutting tools on said shaft, means for intermittently moving said conveyor, means for causing the tools on said travelling carriage to operate on a glass sheet while said sheet is stationary, means for causing the tools on said stationary shaft to operate on a glass sheet while the sheet is moving thereunder, a stop for determining the correct position of a glass sheet on the conveyor longitudinally thereof, a spring normally holding said stop in the path of the glass sheets, and means on said travelling carriage for moving said stop out of the path of the glass sheets when said tools on the carriage reach the end of their operation on a glass sheet.

5. In a machine for cutting glass the combination of a machine frame, an endless conveyor on said frame, a carriage mounted for travel above and across said conveyor, a set of cutting tools on said carriage, a shaft on said machine frame extending over and across said conveyor, a set of cutting tools on said shaft, means for alternately and interdependently effecting the advance movement of said carriage across said conveyor while the latter is maintained at rest and then effecting the return movement of said carriage while said conveyor is advanced, means for raising said tools on the carriage from a glass sheet on said conveyor at the end of said advance movement of said carriage, means for locking said tools on the carriage in their raised positions at the end of said advance movement of the carriage, means operative during the end portion of said return movement of the carriage for conditioning said locking means for release thereof, means releasing said locking means at the end of said return movement of said carriage and while said conditioning means are operative, said conditioning means being further operative at the beginning of the advance movement of said carriage for gradually lowering the released tools on said carriage onto a glass sheet on said conveyor, means for raising the tools on said shaft away from a glass sheet on the conveyor and for releasing said tools on the shaft for gravitational movement onto the glass sheet, means responsive to the passage of the leading and trailing edges of successive glass sheets on

said conveyor for controlling said raising and releasing means of the tools on said shaft, and means operative when said tools on the shaft are released from their raised position for gradually lowering the last mentioned tools onto a glass sheet on the moving conveyor.

6. In a machine for cutting glass the combination of a machine frame, an endless conveyor on said frame, a carriage mounted for reciprocating travel above and across said conveyor, a first set of cutting tools on said carriage, a stationary shaft on said machine frame extending over and across said conveyor, a second set of cutting tools on said shaft, means operative to alternately and interdependently effect the movements of said carriage and said conveyor so that said carriage is advanced over said conveyor while the latter is at rest and then the carriage is returned while the conveyor is simultaneously advanced, means operative to raise said first tools from a glass sheet on the conveyor during the end portion of the advance movement of said carriage, locking means operative at the end of the advance movement of the carriage to lock said first tools in their raised positions, means independent of said raising means operative to effect further raising of said first tools during the end portion of the return movement of said carriage for conditioning said locking means for release thereof, means operative to release said locking means at the end of said return movement of the carriage, said means effecting further raising of said first tools during the end portion of said return movement also being operative to gradually lower the released tools onto a glass sheet on said conveyor during the initial portion of the advance movement of said carriage, means for raising said second tools away from a glass sheet on said conveyor and for releasing said second tools for gravitational movement onto a glass sheet on the conveyor, means responsive to the passage of the leading and trailing edges of successive glass sheets on said conveyor and controlling said raising and releasing means, and means intercepting the gravitational movement of the released second tools and operative to gradually lower said released second tools onto a glass sheet on the moving conveyor.

7. In a machine for cutting glass, the combination according to claim 5, wherein said tools on the shaft are rockably mounted on the latter; and wherein said means for raising and releasing said tools on the shaft includes a yoke rockable on said shaft and engageable below said tools on the latter, an electro-magnet mounted on said frame and, when energized, acting on said yoke to swing the latter in the direction raising said tools engaged by said yoke, and said means responsive to the passage of the leading and trailing edges of the glass sheets includes a normally closed switch, an electric circuit having said switch interposed therein for normally energizing said electro-magnet, and a switch actuator extending into the path of glass sheets on said conveyor and operatively associated with said switch to open the latter upon contact with the leading edge of a glass sheet and to maintain said switch in its open condition until the trailing edge of the glass sheet has passed from under said switch actuator.

8. In a machine for cutting glass, the combination according to claim 5 further including, means arranged at a side of said conveyor operative to transversely position the successive glass sheets on the latter, and means arranged above said conveyor operative to determine the longi-

tudinal position of successive glass sheets on the conveyor.

9. In a machine for cutting glass, the combination as set forth in claim 5; wherein said conveyor includes sprockets rotatably carried by said frame, laterally spaced endless chains meshing with said sprockets and trained therearound, slats extending between said chains and secured thereto, longitudinal guides on said frame, and grooved bearing plates on said slats slidably engaging said guides.

10. In a machine for cutting glass, the combination as set forth in claim 5; including adjustable means mounting said shaft on said machine frame for adjustment toward and away from the path of travel of said carriage by distances which are substantially equal to multiples of the lengths of the glass sheets on said conveyor.

11. In a machine for cutting glass, the combination as set forth in claim 5; wherein said means for alternately and interdependently effecting the advance and return movement of said carriage and the advance of said conveyor includes means for automatically reversing the direction of movement of said carriage at the end of said advance movement thereof, means operative to start the movement of said conveyor, an abutment moving with said carriage, and means actuated by

said abutment to render said starting means operative when said carriage reaches the end of the advance movement thereof.
